UNITED STATES PATENT OFFICE.

LIONELLO GANUCCI-CANCELLIERI AND ANCHISE CAPPELLETTI, OF FLORENCE, ITALY.

STOPPER FOR BOTTLES AND OTHER RECEPTACLES.

No. 885,743

Specification of Letters Patent. Patented April 28, 1908.

Application filed March 2, 1907. Serial No. 360,297.

To all whom it may concern:

Be it known that we, LIONELLO GANUCCI-CANCELLIERI and ANCHISE CAPPELLETTI, subjects of the King of Italy, residing at 5 Florence, Italy, have invented new and useful Improvements in Stoppers for Bottles and other Receptacles, of which the following is a specification.

This invention has for its object the closing of any receptacle containing liquids or solids of no matter what kinds which are to be placed on sale or exported, in such a way that they cannot be opened without breaking the receptacle itself. It is based on the 15 principle of the introduction into a chamber provided in the neck of the flask, or any other receptacle, of a diaphragm of metal, or other suitable material, arranged in such a way that when it is inserted, it can no longer 20 leave same again.

Consequently the invention consists in two parts, of which one forms part of the receptacle to which it is permanently connected and which is called the "chamber," 25 while the other, which is movable and independent, we shall call the "diaphragm."

The accompanying drawings illustrate the invention. Figure 1 represents, in front elevation, the neck of the bottle, or of any other 30 receptacle in which the above mentioned chamber is provided; Fig. 2 illustrates the same in vertical section and Fig. 3 in plan. Fig. 4 is a bottom view of one portion of the diaphragm; Fig. 5 is a section thereof; Figs. 35 6 and 7 show a bottom view and a section, respectively, of the other part of the diaphragm; Fig. 8 shows an opening tool.

The chamber *a* is constituted by an exterior enlargement of the wall forming the 40 neck *b* of the flask or any other receptacle. It must be of such dimensions that the diaphragm *c* can be introduced therein and attain the necessary extension each time that the flask is closed. Although the drawing 45 represents this chamber elliptical in form, it may be varied considerably (circular, triangular, rectangular, star shaped, fan shaped, polygonal with no matter what number of sides, or with a mixed contour, that is to say 50 curves and straight parts) and moreover of no matter what design or figure, but always in strict connection and correspondence with the form of the diaphragm, so that in varying the one it is necessarily requisite to vary the 55 other and reciprocally.

The diaphragm, independently of its form

and considering it only in relation to its essential organs for the operation, is composed of two parts or two thin sheets, superposed one over the other, of metal, or any 60 other suitable material.

The upper part of the diaphragm illustrated separately in Fig. 4, from the under side, and in Fig. 5, in section, serves also as a guide to the lower part; with this object, it 65 has its lateral edges *d*, *d* turned down underneath. It moreover bears towards one of its extremities a bend *e*, having the form of a saw tooth, which presents the hollow to the upper face and a corresponding projection on 70 the opposite side. On the upper face may be printed any marks which may be considered desirable.

The lower part of the diaphragm, illustrated separately, from the under side, in 75 Fig. 6, and in section in Fig. 7, also consists in a sheet which as a whole (that is to say with regard to area and form) is almost identical with the upper part; but it is formed in the following manner: It bears at one of its 80 extremities a small tail *f* which serves as a point of pressure when it is desired to slide one sheet on the other and permits, therefore, of imparting to the diaphragm its maximum length, after it has been introduced into the 85 chamber. At its opposite extremity it carries three tongues, the two lateral and flat ones *g*, *g*, of which are introduced into the folded over edges *d*, *d*, of the other sheet and serve as a guide for the third (tongue) 90 central one *h*, slightly curved upwards and formed throughout its length with a rib which serves to strengthen it and to increase its elasticity, for it is to act as a spring.

Operation. After the flask, or any other receptacle, has been filled and stoppered if it is necessary, with the cork *i*, so that the chamber in the neck remains completely empty and free, into such chamber is introduced the diaphragm with the sheets exactly superposed so that they present the smallest area and that it may be possible to introduce them. Then, by holding the upper sheet stationary and by means of a small tool pushing against the tail *f* of the under sheet, they 100 will be caused to slide one over the other, until the central tongue *h* has passed over the projection formed by the tooth *e*. Then, the diaphragm will occupy the entire interior surface of the chamber and it can no longer be 105 withdrawn therefrom, without the edges of the chamber being broken, because the cen-

tral tongue *h*, pressing against the tooth *e*, presents an absolute obstacle to the sheets of the diaphragm being superposed. It must be added that (when it is a question of a flask 5 entirely of glass) for facilities of carrying the chamber and the diaphragm, the inventors have thought of making a circular partial incision *l*, on the exterior surface beneath the chamber *a* of the flask. This incision, 10 which for a very small part of its travel is accentuated in such a way that it becomes complete and forms a hole *p*, which renders the fracturing of the upper part of the flask or any other receptacle easy, by means of a 15 suitable tool illustrated in Fig. 8. This tool is formed with a ring *n*, into which the whole of the upper part of the flask can pass. Consequently in the case of an elliptical chamber, it will be made elliptic; but the chamber be- 20 ing of another form, the tool must be such that the upper part of the flask or other receptacle, may enter it. After having introduced the head of the flask or receptacle, into the ring *n*, the ring is turned, causing it to 25 make one quarter of a revolution; then the ring can no longer be withdrawn. By causing the point *o* to enter the hole *p* and employing the handle *q* as a lever, the neck of the flask, or other receptacle, will be frac- 30 tured exactly along the line of the incision; consequently, the part of the neck which contains the chamber *a* with the diaphragm, can be removed with facility; after which the cork situated therein is withdrawn by a cork- 35 screw. The handle *q* may be made in the form of a corkscrew (Fig. 8) so as to require a single tool instead of two. After having re-

moved the chamber from the neck of the receptacle, the whole of the closing apparatus is missing, consequently, it evidently follows 40 that the receptacle has been broken and opened; however the receptacle may be still used as an ordinary receptacle. The neck of the flask may be formed with a second rim *m*, for strength, but this is not indispensable. 45

What we claim as our invention, and desire to secure by Letters Patent, is—

1. The combination, with a vessel having an orifice to be stopped, provided with interior shoulders, a stopper adapted to close said orifice and means for preventing the withdrawal of said stopper, said means comprising two parts, one sliding on the other and adapted to engage with the interior shoulder when expanded, and means for locking the 55 parts in their expanded position.

2. A bottle having an annular groove in its neck, a stopper for the bottle and means for preventing the withdrawal of the stopper, said means consisting of two interlocking 60 parts, one sliding on the other and adapted to be expanded to engage the groove, each part having a projecting portion thereon which engage with each other to lock the parts in their expanded position.

In testimony whereof we have signed our names to this specification in the presence of two subscribing witnesses.

LIONELLO GANUCCI-CANCELLIERI.
ANCHISE CAPPELLETTI.
